UNITED STATES PATENT OFFICE.

HARRY D. NEFF, OF NEWPORT, PENNSYLVANIA.

EXTENSION HANDLE FOR WRENCHES.

Application filed May 15, 1928. Serial No. 278,010.

My present invention relates to wrenches, and more particularly to novel extension handles for wrenches.

One object of the present invention is the provision of an extension handle which will be economical to manufacture and simple to operate.

Another object of the invention is to devise an extension handle which will be strong, durable, rugged and efficient.

A further object is to so construct my novel extension handle that when used with a wrench, either a straight or an S-wrench, the pull or strain point will be located at the strongest point of the wrench, instead of on the weak side of the head, as in present methods.

A further feature of the present invention is that each extension handle can be made to accommodate several different sizes of open end wrenches, as many as four or five. Thus but two extension handles constructed according to my invention will be required for the handling of an entire set of open end wrenches.

My novel extension handle may be made in a single drop forging, requiring but one trimming operation and one punching operation, and when properly hardened or tempered will last indefinitely.

My novel handle, therefore, comprises but a single piece, having no relatively delicate and expensive mechanism to get out of order, a feature which will appeal to mechanics and others skilled in these arts.

The above and other objects and features of the invention, details of construction, methods of application, and advantages, will be hereinafter more fully pointed out, described and claimed.

Referring to the drawings, illustrated preferred embodiments of the present invention,

Fig. 1 is a side elevation of my novel extension handle in position on an open end wrench;

Fig. 2 is a top plan view of the structure of Fig. 1;

Fig. 3 is a side elevation of a slightly modified form of handle; and

Fig. 4 is a top plan view of the structure of Fig. 3.

Referring now to the drawings, and particularly to Figs. 1 and 2, for a particular description of the invention, its construction,

application and operation, my present novel extension handle comprises a handle proper 1, which, of course, will be of any desired or predetermined length. This handle has a pair of forwardly extending parallel sides 2 formed integral with the handle 1 through the medium of two inclined portions 3. Between the forward ends of these sides 2 is a crossbar 4, said crossbar being below the upper edges of said sides 2 and above the lower edges of said sides. The sides 2 are then inclined upwardly and forwardly, as at 5 and from which two side portions 6 extend forwardly and are then inclined inwardly, as at 7, being solid across their outer ends or union. In the extreme forward portion of the device a groove 8 is formed, of approximately the same width as the thickness of the handle of the wrench 9.

Between the sides 2 is a recess 10 of a sufficient size to receive the head 11 of the wrench 9.

When applying this extension handle to a wrench 9, the head 11 of the wrench is inserted over the crossbar 4 and the wrench then straightened, which brings the head 11 down into the recess 10, where it is protected against lateral slippage or displacement by the sides 2, and the shank 9 is seated in the groove 8, which affords a firm seat therefor. In this manner the pull or strain point is located at the strongest part of the wrench, viz., below the head 11, thus affording an extremely strong rugged device, and enabling great strains to be put on the wrench and extension handle without breakage or damage. The major pull of the extension handle will be away from the wrench 9, and longitudinal slippage of the extension handle in this direction will be prevented by the manner and position in which the head 11 fits over the cross-bar 4. Thus an extremely strong, rugged, efficient and quick-acting extension handle is produced, which may be made in a very economical manner as a single drop forging, requiring but one trimming operation and one punching operation. The advantageous features of my novel extension handle will appeal to mechanics, machinists, and others by whom these implements are utilized.

In Figs. 3 and 4 I have illustrated a slight modification, wherein the handle 15 has the parallel sides 16 inclined upwardly from said

handle and being united thereto by the inclined portions 17. In this handle the crossbar 18 is positioned above the axis of the handle 15, instead of being in a line therewith as in Figs. 1 and 2. The forward end 19 of the handle, is formed with the groove 23 in which the shank 20 of a wrench is adapted to closely fit.

The opening in the head 21 of this wrench 20 is illustrated as engaging the crossbar 18, although a recess 22 is provided in which the head 21 may seat similar to the arrangement in Figs. 1 and 2. This construction of Figs. 3 and 4 differs but slightly from 15 the structure of Figs. 1 and 2, and is equally as economical to manufacture, rugged, strong and efficient in operation. In each instance the pull leverage is substantially central of the wrenches 9 and 20. Each of the extension 20 handles 1 and 15 will accommodate a wide range of wrench sizes, it being my present intention to construct two sizes of handles to take care of an entire set of wrenches.

I believe that the extension handles illustrated and described in this application are novel, and I have therefore claimed the same herein, said claims being drawn to the novel features of these extension handles, as I am aware that an extension handle *per se* is 30 not broadly novel.

While I have necessarily described my present invention somewhat in detail, it will be appreciated that I may vary the size, shape and arrangement of parts within reasonably wide limits without departing from 35 the spirit of the invention.

My invention is further described and defined in the form of claims as follows:

1. An extension handle for wrenches comprising a handle portion, two parallel sides 40 extending forwardly of and each united to the handle portion by a relatively short inclined portion, a crossbar uniting said sides, said crossbar, sides and handle portion forming a recess of a size to receive the head of 45 a wrench, the forward ends of said sides being inclined inwardly to a union having a groove therein to receive the shank of a wrench whose head seats in said recess, said crossbar, sides and union forming a recess to 50 permit the passage therethrough of the head of said wrench.

2. An extension handle for wrenches comprising a handle portion, two parallel sides extending forwardly of and each united to 55 the handle portion by a relatively short inclined portion, a crossbar uniting said sides, said crossbar, sides and handle portion forming a recess of a size to receive the head of a wrench, the forward ends of said sides 60 being inclined inwardly to a union having a groove therein to receive the shank of a wrench whose head seats in said recess, said crossbar, sides and union forming a recess to 65 permit the passage therethrough of the head of said wrench, the forward portion of said sides, at their union, being on a plane above that of the handle portion.

In testimony whereof, I have signed my name to this specification.

HARRY D. NEFF.
